UNITED STATES PATENT OFFICE

167,984

CARPET

Robert Heller, New York, N. Y., assignor to C. H. Masland & Sons, Carlisle, Pa., a corporation of Pennsylvania

Application June 26, 1952, Serial No. 20,353

Term of patent 14 years

(Cl. D92—4)

To all whom it may concern:

Be it known that I, Robert Heller, a citizen of the United States, residing at 161 East 61st Street, New York city 21, State of New York, have invented a new, original, and ornamental Design for Carpet, of which the following is a specification, reference being had to the accompanying drawing, forming a part hereof.

The drawing is a plan view of a carpet showing my new design; the design unit being indicated by broken lines and repeated as shown throughout the fabric.

The opposite face of the carpet shown is plain.
I claim:

The ornamental design for a carpet, as shown and described.

ROBERT HELLER.
